GRIPPING DEVICE FOR BUTTONS OR PINS

Mickail Platis, Astoria, N. Y., assignor of one-half
to Adolph Dick, Brooklyn, N. Y.

Application May 21, 1951, Serial No. 227,383

2 Claims. (Cl. 24—158)

1

My invention is an improved holding or fastening device; and particularly a locking or retaining member for securing buttons and other parts to a garment and facilitate the attachment, removal and replacement thereof.

An important object of this invention is to provide a retaining member for the buttons, bars, badges, emblems and other insignia intended for uniforms; but of course the device can be readily used for mounting similar objects on ordinary garments.

A further object is to provide a holding or fastening device which is very efficient in action and can easily be manipulated to engage the object to be affixed to a garment at two or more points, and easily dismounted to release the object if necessary.

These and other objects and advantages are fully described herein, and several embodiments of the improvement are illustrated in the drawings. But variations in structural details can of course be adopted without omission or material alteration of any of the essential characteristics which are defined in the claims.

On said drawings the figure shows a button or the like insignia and a holding or retaining member, with the parts all separated from one another.

As indicated in the figure, my invention is intended to facilitate attaching to a garment an accessory such as a button, that has a convex or bulging top or front part 1 and a flat rear part 2. The front part is a hollow bowl-shaped element, and the part 2 is a round plate that can be fitted to the top or crown 1 and secured around the edges in any suitable manner, so that the two parts will be permanently joined together. The back plate 2 has cut out projections or fingers 3 and a central aperture 4 which is in line with an aperture 5 in the crown 1 when the crown 1 and back plate 2 are united. In the back plate also are cuts or slits 6 which radiate from the opening 4 and divide the plate 2 into flexible sections 7. To the convex face of the part 1 I can affix a member 8, which can be a letter, number or other insignie or emblem, having a threaded stud at the center. This stud is inserted into the opening 5 and turned till the threads engage the opening 4 in the back plate to make it fast, and the stud also acts to hold the crown 1 and back plate 2 in assembled positions.

The button can be finished so as to serve for a uniform or other special dress, and it is put on the garment by first transfixing the projections or fingers 3 through the fabric thereof. The

2

button is then made fast by a retaining member made up of the parts 11, 10 and 12, all of the same outline and area. The part 10 is the bottom plate for the retaining or locking member, and it has apertures 13 to receive the fingers 3. This plate is affixed by suitable means to the part 12 which is the cover, and between the parts 10 and 12 is the part 11, that has the form of a plate with resilient bent tabs 14 cut from the plate 11, the tabs 14 having slots 15 through which the fingers 3 are passed; and the tabs 14 are cut free from the plate 11 at the middle of the plate and along the sides, but are connected to the plate 11 near its ends and doubled over to project beyond said ends. The top is arched and has a rim 16 and openings 17 in the top in line with the slots 15 and apertures 13 in the bottom 10; the rim 16 making contact with the plate 11 around the edges thereof. When the parts 10, 11 and 12 are assembled they are made fast to one another by suitable means, and the button is affixed to the garment by forcing the fingers 3 through the openings 13 and slots 15 in the tabs 14; first piercing the fabric of the garment from the front with the fingers 3. The ends of the tabs 14 project through the apertures 13, and the tab-carrying plate 11 is slotted on three sides of each tab 14 to mark off gripping elements or dogs 18. Recesses 19 are provided at the center of the slots on the inside edges of the plate 11 for engagement with the fingers 3. When the fingers 3 penetrate the holding member, the fingers are forced by the dogs 18 against the edges of the recesses 19. To release the fingers 3, the tabs 14 are pressed towards each other, lifting the dogs 18 and disengaging them from the fingers 3. Then the button can be detached.

Having described my invention, what I believe to be new is:

1. A device for securing to a garment an object having transfixing projections, said device comprising a retaining member to receive said projections, and having a bottom plate with openings for said projections, a second plate on said bottom plate having flexible gripping elements to engage said projections, and tabs attached to said elements and bent outward over the extremities of said plate.

2. The securing device of claim 1 wherein said elements are in the plane of the second plate and secured thereto each at one end adjacent the middle of the second plate; said elements extending towards the extremities of said plate with their opposite ends adjacent said extremities and

said openings, said tabs being fixed to said elements adjacent the opposite ends thereof.
